UNITED STATES PATENT OFFICE.

LOUIS D. GREGG, OF HACKENSACK, NEW JERSEY, ASSIGNOR TO THE GREGG COMPANY, LIMITED, OF NEW YORK, N. Y., A CORPORATION OF NEW YORK.

CANE CAR AND THE LIKE.

Application filed July 6, 1925. Serial No. 41,662.

This invention relates primarily to railway or other cars of the type employed for the transportation of sugar cane, although not limited to this specific use, and, more particularly, to the support in such cars of the end stakes upon the underframe.

In cars of this type constructed with wooden underframes, it is usual to bolt the end stakes both to the inner face of an end sill and to the side of a longitudinal sill. If framed into or otherwise supported solely upon the end sill the stakes are apt to split or to twist and pry loose the sill, especially when, as is commonly the case, the opposite end stakes are not tied together at the top by a longitudinal rail, the stakes then acting as lever arms against which the outward thrust of the load thereon is exerted. While the rigidity of the stakes is increased by attaching each to a longitudinal as well as end sill the supporting arms of the stakes, by which the lever action mentioned is to be resisted, are still limited to a length not exceeding the depth of the frame members. Moreover, it is often desirable to provide a maximum distance between the opposite end stakes, in order to permit of a maximum load, with a minimum length of underframe, which in many cases is limited by track or other conditions.

The same problem is involved in steel construction, but not to the same degree.

My present invention, by which I have obviated the above defects, consists, briefly, in providing supporting means for the end stakes which will permit them to be placed over or even outside the end sills, if desired, for the purpose of obtaining the maximum inside length, while at the same time providing for them a more extended anchorage and therefore more rigid support than heretofore upon the longitudinal sills without obstructing the sides and thereby interfering with the free discharge of the load therefrom.

The invention is shown, by way of illustration and not of limitation, in the accompanying drawings, in which—

Figure 1 is a perspective view of an end of the underframe of a car with end stakes mounted thereon, illustrating one practical embodiment of my invention; Fig. 2 is a view of the same parts in side elevation, slightly enlarged, with the upper ends of the stakes broken away and with flooring and

end wall sheathing added; Figs. 3 and 4 are details illustrating, in side and inner end elevation respectively, a modified form of the support of an end stake on the underframe; and Fig. 5 is a detail showing, in side elevation, an end stake mounted upon a steel underframe, illustrating a further modification of the invention.

Referring first to Figs. 1 and 2, the wooden underframe comprises the longitudinal sills 11 and end sill 12. The three end stakes 13 are mounted above the end sill and flush with its outer face. Each of these stakes is supported by and between two channel pieces 14, which are bent to elbow shape with an inclined or diagonal portion intermediate the vertical upper and horizontal lower arms, the outer channel of each corner stake support being preferably extended, as at 15, to the upper end of the stake. The two of each pair of channels are joined at their upper ends, or at the upper end of the shorter piece, by outer and inner plates or bars 16—17 which are riveted to their flanges and serve to confine the stake between the channels, centrally by a flanged elbow 18—80 either a casting or preferably a short channel section bent to shape—which is riveted to the webs of the diagonal portions of the channels and, seated upon the top of a longitudinal sill, is bolted both to the lower end of the stake by the bolt 19 and to the end sill by the bolt 20, and at their lower inner ends, straddling the longitudinal sill, by shaped straps 21—22 which bear upon the bottom and top faces of the sill and are bolted at their flanged ends to the lower and upper flanges respectively of the channels. Sufficient clearance is left between the ends of the straps and the flanges of the channels so that by loosening the upper bolts and tightening the lower bolts or vice versa the upper arms of the several supports, and the stakes carried thereby, may be brought into alignment in the same vertical plane. The upper ends of the stakes are preferably joined by a top rail 23, of inverted channel section. The stakes are thus positioned at the extreme end of the underframe but are supported entirely, or substantially so, upon the longitudinal sills, being supported and fulcrumed upon the top of the sills by the elbows 18 and anchored thereto at the ends of the inwardly extended horizontal arms

of the channels; and by extending the flooring, as by the plank 24 (Fig. 2), over the inclined portion of the channels these parts are covered so that they will not interfere 5 with the free discharge of the load from the sides of the car.

In the modification illustrated in Figs. 3 and 4, the stake 13¹ is supported upon the longitudinal sill 11 of the underframe by a 10 single channel piece 14¹ which is bent in a curve to elbow shape. The lower end of the stake, fitting between the flanges of the vertical arm of the channel, is secured to its web by a bolt 19¹ and by a second bolt 20¹ 15 extending through the web of the channel and through the sill and the downwardly flanged inner end of a plate 18¹ which at its upwardly flanged outer end is riveted to the web of the channel and by which the 20 channel, and the stake, are supported or fulcrumed upon the top of the sill. The lower horizontal arm of the channel support is anchored at its end to the bottom of the sill by a plate or strap 21¹ which at 25 its outer end is bolted to the lower web of the channel and at its upwardly flanged rear end is bolted to the web of the channel by a bolt 22¹ extending through the sill.

It is obvious that in both of the forms 30 hereinabove described the channels may, if desired, be extended to the height required and so provide metallic stakes with integral elbow supports, the wooden stakes being omitted entirely.

55 As illustrated in Fig. 5, the longitudinal sill 11² and end sill 12² of the underframe and the end stake 13² are all of steel channel sections and are riveted together, the flanges of the end sill to the flanges of the longitudinal sill, and the inner flange of the stake to the web of the end sill. The stake, thus supported on the end sill beyond the end of the underframe, is braced and anchored back upon the longitudinal sill by a relatively 45 heavy inclined or diagonal plate 14² which extends the entire width of the car and at its flanged upper edge is riveted to the inner flange of the stake and at its lower flanged edge to the upper flange of the longitudinal sill and, similarly, to each of the 50 other stakes and sills. The combined inclined anchorage and corner floor member here shown is also applicable to wooden constructions.

55 It is to be understood that the invention may be further modified in its details, without departing from the spirit or sacrificing the substantial advantages thereof.

What I claim as new, and desire to secure 60 by Letters Patent, is—

1. In a vehicle of the type described, the combination with an underframe comprising longitudinal and end sills, a flooring therefor, and stakes, of stake supporting 65 means providing a support for a stake at

a point above the underframe and a connection therefrom extending below the surface of the flooring to an anchorage on a longitudinal sill at a point back from the inner face of the stake. 70

2. In a vehicle of the type described, the combination with an underframe comprising longitudinal and end sills of end stakes and of stake-supporting means which include diagonally disposed elements affording support for the stakes at a point above the top of the underframe and anchoring them inwardly to the longitudinal sills at a point substantially removed from the inner faces of the stakes and so connected 75 transversely of the underframe as to provide an upwardly and outwardly inclined extension of the flooring. 80

3. In a vehicle of the type described, the combination with an underframe comprising longitudinal and end sills of an end stake and, for the support thereof, an elbow member to the vertical arm of which the stake is secured and which centrally is supported and fulcrumed on the upper edge 85 of the longitudinal sill and the end of its inwardly extending horizontal arm is anchored to the lower part of the sill. 90

4. In a vehicle of the type described, the combination with an underframe comprising longitudinal and end sills, of an integral metallic end stake and elbow support which at or near the bend of the elbow is supported upon a longitudinal sill and is anchored thereto at the end of the inwardly extending 95 horizontal elbow arm. 100

5. In a vehicle of the type described, the combination with an underframe comprising longitudinal and end sills of end stakes for an end wall and means located outside 105 the inner face of the end wall and below the flooring of the vehicle for supporting said stakes upon the longitudinal sills in position over the end sills. 110

6. In a vehicle of the type described, the combination with an underframe comprising longitudinal and end sills of end stakes and means for supporting said stakes upon the longitudinal sills in position outside the inner face of an end sill without obstructing 115 the open sides of the vehicle above the flooring thereof. 115

7. A vehicle of the type described comprising longitudinal and end sills, end stakes which are positioned outside the inner faces 120 of the end sills, and means for anchoring said stakes inwardly to the longitudinal sills which include diagonally disposed elements so connected transversely of the underframe as to provide an upwardly and outwardly inclined extension of the flooring substantially 125 to the inner faces of the stakes. 130

8. A vehicle of the type described comprising longitudinal and end sills, an end stake, and as a support for the stake a member 130

which is bent to elbow shape with a diagonal portion intermediate its vertical and horizontal arms and which at such intermediate portion is supported upon the top of the longitudinal sill and at the end of its inwardly extending horizontal arm is anchored to the said sill.

9. A vehicle of the type described comprising longitudinal and end sills and metallic end stakes which at their lower ends have two bends forming an intermediate inclined section and a horizontal elbow arm and which are each at such intermediate inclined section supported upon a longitudinal sill and at the end of the inwardly extending horizontal elbow arm anchored to said sill.

10. A vehicle of the type described comprising longitudinal and end sills, end stakes which are supported by elbow-shaped members having a diagonal portion intermediate the vertical and longitudinal arms and each supported at such intermediate portion upon a longitudinal sill and anchored thereto at the end of the inwardly extending horizontal arm, and a transverse flooring member connecting and covering the diagonal portions of the several stake-supporting members.

11. In a vehicle of the type described, the combination of a longitudinal sill, an end sill, an end stake, and means for supporting the stake upon the longitudinal sill in position over the end sill comprising two members which are bent to elbow shape with an inclined portion intermediate their vertical and horizontal arms, means for securing the end stake between the vertical arms of the members, means joining the intermediate portions of the members and adapted to bear upon the top of the longitudinal sill, and means for anchoring the inwardly extending

horizontal arms of the members to the said sill on the opposite side thereof.

12. A vehicle of the type described, comprising a longitudinal sill, an end sill, an end stake, and means for supporting the stake upon the longitudinal sill in position over the end sill comprising two members of elbow shape with a diagonal portion intermediate their vertical and horizontal arms, an elbow piece secured to the intermediate portion of the two members and providing a bearing therefor on the top of the longitudinal sill, and upper and lower straps adapted to connect the horizontal arms of the members above and below the longitudinal sill and to provide adjustable means for their anchorage thereon.

13. In a vehicle of the type described, the combination of a longitudinal sill, an end sill, and an end stake comprising two spaced members each bent at their lower ends to elbow shape with a diagonal portion intermediate their vertical and horizontal arms, an elbow piece secured to the intermediate portion of the two members and providing a bearing therefor on the top of the longitudinal sill, and means for anchoring the horizontal arms of the members to the longitudinal sill, one on each side thereof, including a strap attached to said members and bearing against the bottom of the sill.

14. A vehicle of the type described comprising an under frame with longitudinal and end sills, end stakes, and means for supporting the stakes on the under frame which include means carrying an inwardly inclined section of flooring and providing an inwardly inclined anchorage for the stakes upon the longitudinal sills.

LOUIS D. GREGG.
